UNITED STATES PATENT OFFICE.

GEORGE H. BROWNE, OF CAMBRIDGE, MASSACHUSETTS.

SKATE.

1,181,831.

Specification of Letters Patent.

Patented May 2, 1916.

Application filed April 7, 1915. Serial No. 19,687.

To all whom it may concern:

Be it known that I, GEORGE H. BROWNE, a citizen of the United States, residing at Cambridge, in the county of Middlesex and 5 State of Massachusetts, have invented certain new and useful Improvements in Skates; and I do hereby declare the following to be a full, clear, and exact description of the invention, such as will enable others 10 skilled in the art to which it appertains to make and use the same, reference being had to the accompanying drawings, and to the letters and figures of reference marked thereon, which form a part of this specifi- 15 cation.

This invention relates to new and useful improvements in a compensating device for rendering efficient a low stanchioned, all-steel skate.

20 One of the greatest handicaps in the progress of artistic skating has been due to the imperfect form of the skate blade, which has made all skating difficult. The secret of all good skating is balance and 25 control; and, since these fundamentals are so hard to get on hitherto available skates, most young people have given up attempts at figure skating for the reason that it is difficult to attain and requires too much 30 practice to secure the required result. The reason for failure to accomplish this difficult feat with the skates as commonly constructed, is that the skates are too high, too nearly level, or even higher at the toe than 35 at the heel, too sharp rocked, or too flat, and seldom located at a point near the middle of the foot, where the skate must be to insure any balance at all.

The object of the present invention is to 40 produce a low skate without the danger of the sole's striking the ice, which would tend to cause the skater to fall; and at the same time to produce a skate which will relieve the ankles without letting the edges of wide- 45 soled shoes interfere, when the body of the person skating is inclined.

It is my aim in the present invention to effect such a change in the design or form 50 of construction of a skate blade as to produce a skate adequate to the most exacting demands of up-to-date scientific skating. I accomplish this by producing a design of blade such as will serve to bring the foot 55 of the skater close to the ice, thereby reduc- ing the strain upon the skate and prevent-

ing the strength of the skater from being unduly overtaxed, at the same time reducing to a minimum the danger of the edge of the boot sole to which the skate is attached contacting with the ice when the 60 body of the skater is inclined in the normal act of skating. This is specifically accomplished by a compensating device incorporated in the construction of the blade which is widest at the point where the danger is most likely to occur. The skate blade which I have shown embraces the unique combination of splay taper and rock of the blade, all of which will be more fully hereinafter described. 70

The present rapid development of artistic skating has required a more efficient skate to meet the exacting requirements of the art. In ordinary plain skating, progression upon the ice is confined to straight zigzag lines, 75 attained by a thrust of one foot and a glide upon the other. To accomplish this, skates of ordinary construction will suffice. For speed skating, long, narrow, flat blades are required but for scientific or fancy skating 80 blades of this description would not meet the requirements. This form of skate and this method of progression would not meet the demands which the most elementary, artistic skating of today makes upon even 85 the least proficient fancy skater. The motive power in most figure skating is generally by the movement of the body inclined out of equilibrium, pushing or pulling against the almost frictionless ice with the 90 edge of the skate. The greatest skill and judgment are, at the present time, required in the construction of the edge for the movements in modern artistic skating are 95 always in curved lines.

My invention is illustrated in the accompanying drawings, in which:

Figure 1 is a side elevation of a skate made in accordance with my invention. Fig. 2 is a bottom plan view. Fig. 3 is a 100 sectional view on line 3-3 of Fig. 1 looking in the direction of the arrow.

Reference now being had to the details of the drawings, 1 designates the blade of the skate having two stanchions 2 and 3, the former of which supports the toe plate 4 and the other the heel plate 5, the point of connection, however, between the toe and heel plates being at one side of the longitudinal center of the respective plates, this 105 110

construction serving to protect the ankle of the skater by preventing the turning of the blade. It will be noted that the front stanchion is farther forward than is usual upon skates, and so positioned as to increase both the efficiency of the skate and the strength of construction (by shortening the free portion of the skate and rendering it less likely to break), at the same time providing a suitable place for my compensating device. The said forward stanchion is made much lower than usual in skates (in the largest sizes not higher than $1\frac{1}{2}$ inches and in the smaller sizes, and ladies' models, still lower).

At or near the point designated by letter *a* (it varies slightly with different sizes), the blade is thickest, adjacent to the rear end of the forward stanchion; and the blade tapers in straight lines from the thickest portion to the heel, as shown clearly in Fig. 2, thereby producing the same effect as a parallel-bladed skate, but facilitating softer changes of edge on the ice, because the skater does not have to turn over so much steel to change from one edge to the other. The blade also tapers from the thick portion to the toe on gentle curves; so that the blade, viewed from the bottom, is of the general shape shown in Fig. 2, the swelling or widening portion being thickest at the point of lowest elevation (usually not over $\frac{3}{16}$ " wide). It is obvious that any inclination of the body of the skater from the perpendicular will tilt the skate sidewise, which will have the effect of producing a sharp rock and compel a turn, thereby relieving the danger of the edges of the sole striking the ice. This is the essential feature of novelty in the present invention, and, combined with this tapering of the blade from the "danger point of striking" is a coöperating sharpening of the "rock" (that is, the curve to which the skate is ground from toe to heel, on the bottom). Between the stanchions, the skate is ground rather flat, to "run on", in big curves. To facilitate executing turns on the ice, the radius of the curve is shortened from each stanchion to the extremities of the blade. While many skates have features whereby certain figures may be made with the blades, the degree of the forward increase of rock and its combination with the forward tapering of the blade, enables the skater on my skate to cut such figures more efficiently and with less danger of striking the edge of the boot than would be possible with the ordinary construction of skate. Hitherto, the skate has generally been ground to a uniform circular curve of a radius varying from $4\frac{1}{2}$ to 7 feet. To distinguish the curve to which the bottom of the skate blade is ground from the curve which it cuts on the ice, we generally call it the "rock" of the skate. Obviously, the flatter the rock, the easier it

is to glide on curves of big radius and the harder it is to execute turns and loops without scraping or bruising the ice. A clean print on the ice is the first requisite of artistic skating; the sharper the rock, the easier it is to execute small curves, loops and turns and the harder it is to glide on big curves and spirals on a stable balance.

An important technical and structural advantage is secured in this new skate by the position of the front stanchion. This is farther forward than in any other skate. This position shortens the forward free portion of the blade and this strengthening enables the manufacturer to apply the innovation without weakening this portion of the blade, which is always more efficient if unattached. The lateral strain on this free toe of the new skate is further relieved by the design of the upturned portion, which enables it to engage in a narrow slot in the welt of the boot and still more free, unattached. The forward position of this stanchion further enables the manufacturer to place the compensating device for the reduced elevation of the skate at just the point where it is most effective for its novel purpose, and also at just the point most effective for coöperating with the changing rock of the blade to overcome the hitherto unsurmountable difficulty in providing a single blade by means of which a skater can execute both big long curves and spirals and also sharp turns and little loops without bruising the ice. The discovery of this point has resulted in the perfection of the invention of a unique shape of blade, which secures for the first time the above mentioned efficiency in a single skate blade adequate to the demands of the highest development of the skating art today and, at the same time, keeps the blade so low that the strength of even so-called weak ankles is not overtaxed and the danger of hitting the edges of the boot sole on the ice when the skater inclines his body is successfully obviated.

The further structural essentials of this invention are as follows: At a point adjacent to the rear of the front stanchion (which is itself well forward), the blade is thickest. From this point backward, in converging straight lines (or edges) the blade narrows to the heel (as much as is compatible with strength); and from this same point forward, as far as the cutting edge is commonly used, the blade tapers in converging curved lines or edges (as much as is compatible with strength); and from this point forward too, the rock of the blade begins to grow sharper rather rapidly, but backward, until almost to the front of the rear stanchion, the rock is very flat (for big curves and spirals). This unique combination of splay, taper and rock (ground, of course, to a soft, continuous, compound curve) at about the

point of lowest elevation, provides a cutting edge of such efficient rock that turns and loops are easily cut clean on it.

The construction of a skate in accordance with my invention preserves all the advantages of the normal parallel or uniformly splayed blade, when ground to a similar curve. By my combined rock and taper, at or near the point of lowest elevation, the 10 skate is given a quality which no other heretofore used has possessed. The compound curve, produced by the taper and the sharpening of the rock, relieves the low skate of all danger of hitting the ice; and a blade 15 is provided which will be efficient both for "running" on big, easy curves and for turning on sharp curves—with a safe skate, lower than heretofore produced, and therefore more serviceable for more kinds of use than 20 ever before in the history of the skating art.

By the provision of a skate made in accordance with my invention, this easy construction of the skate renders it particularly available for beginners of both sexes, with 25 weak or strong ankles, and also for pair-skating.

What I claim to be new is:—

1. In a skate of the character described,

Copies of this patent may be obtained for five cents each, by addressing the "Commissioner of Patents,
Washington, D. C."

a skate blade having its thickest part at a point slightly to the rear of the front stanchion of the skate and converging from this point in straight lines to the thinnest part of the blade at the heel, as shown and described. 30

2. In a skate of the character described, 35 a skate blade having its thickest part at a point slightly to the rear of the front stanchion of the skate and converging from this point in curved lines to the extreme forward end of the cutting edge of the blade in normal use, as shown and described. 40

3. A skate of the character described, comprising a skate blade having its thickest part at a point slightly to the rear of the front stanchion of the skate and converging from 45 this point in straight lines to the thinnest part of the blade at the heel and converging in curved lines to the extreme forward end of the cutting edge of the blade in normal use, as shown and described. 50

In testimony whereof I hereunto affix my signature in presence of two witnesses.

GEORGE H. BROWNE.
